FIG. 1 is a perspective view of a storage album for tape cassettes or the like showing my new design in a partially opened position with a portion of the upper left area being broken away;

FIG. 2 is a rear perspective view thereof in a partially closed condition, the side opposite that seen being the same in appearance as the side shown;

FIG. 3 is a front elevational view in a closed condition;

FIG. 4 is a bottom view in a fully open condition; and

FIG. 5 is a top view thereof in a closed condition.

This application is a division of co-pending application Ser. No. D-22,480, filed Apr. 17, 1970.

I claim:

The ornamental design for a storage album for tape cassettes or the like, as shown and described.
